COMBINED LAMP REFLECTOR AND DIFFUSER

Michael G. Conrad, Detroit, Mich., assignor to Duralastic
Lamp Products Company, Detroit, Mich.

Filed Oct. 5, 1972, Ser. No. 295,383

Term of patent 14 years

Int. Cl. D26—05

U.S. Cl. D46—16 C

FIG. 1

FIG. 2

FIG. 3

FIG. 1 is a perspective view of a combined lamp reflector and diffuser embodying my design.

FIG. 2 is a bottom plan view of the lamp globe shown in FIG. 1.

FIG. 3 is a sectional view taken substantially along the line 3—3 of FIG. 2.

I claim:

The ornamental design for a combined lamp reflector and diffuser, substantially as shown and described.
